UNITED STATES PATENT OFFICE

ARTHUR R. McARTHUR, OF GARY, INDIANA, ASSIGNOR TO AMERICAN SHEET AND TIN PLATE COMPANY, A CORPORATION OF NEW JERSEY

PACK OPENER

Application filed October 19, 1928. Serial No. 313,544.

This invention relates to pack openers and, more particularly, to pack openers for opening or separating the several sheets of 5 packs of hot rolled sheets or plates, and has for its object the provision of a novel pack opener adapted to work the packs of sheets as they are passed therethrough so as to break the bond between the sheets.

Another object of my invention is to provide suitable guides so spaced and arranged 10 that they will provide breaking edges against which the pack may be worked.

In the drawings—

Figure 1 is a plan of a pack opener constructed in accordance with this invention.

Figure 2 is a sectional elevation taken on the line II—II of Figure 1.

Figure 3 is a sectional elevation taken on the line III—III of Figure 2.

Referring more particularly to the drawings, the main frame of the machine consists of a base 2 and a pair of spaced side 20 housings 3 and 4.

A pair of horizontal feed-in pinch rollers 25 5 and 6 are journaled in suitable bearings in the side housings at the rear or entrance end of the machine, and a pair of horizontal feed-out pinch rollers 7 and 8 are journaled in suitable bearings in the side housings at 30 the forward or exit end of the machine.

The space between the pairs of pinch rollers 5 and 6 and 7 and 8 is bridged by a pair of vertically spaced guide members 9 and 10. The guide members 9 and 10 have 35 their central portions cut away in skeleton form leaving continuous or solid transverse guide sections adjacent both the feed-in and feed-out pinch rollers, which sections are connected by relatively narrow connection strips 12.

The continuous or solid transverse guide sections adjacent the feed-in pinch rollers are designated by the numeral 13 and extend substantially parallel with each other 45 on a horizontal plane. These sections 13 of the guides 9 and 10 are spaced apart only sufficiently to permit a relatively slight or workable clearance for the packs of sheets or plates to be opened.

The guides 9 and 10 are arched upwardly

and downwardly from the solid sections 13 so as to provide clearance for working the packs of sheets or plates.

A pair of rotary beaters are mounted intermediate the pairs of pinch rollers and 55 are composed of shafts 15 which are journaled in suitable bearings in the side housings 3 and 4, and are provided with beater arms 16. The beater arms 16 are preferably mounted at diametrically opposite points 60 on the shafts 15 and are formed in sections which are spaced along the shafts 15 so as to provide clearance spaces for the connecting strips 12 of the guides.

The beaters are preferably arranged so 65 that the beater arms 16 of the top beater will extend at right angles to the beater arms 16 of the lower beater, and the beaters are adapted to be maintained in this relation and operated in unison by means of 70 gears 18 and 19, mounted on the respective beater shafts 15 and meshed together. The upper beater shaft 15 is connected directly to the armature shaft 20 of a motor 21 by a coupling 22.

The pinch rollers 5 and 6 are connected by gears 23 and 24 and the pinch rollers 7 and 8 are connected by gears 25 and 26. The upper pinch rolls 5 and 7, of the respective pairs of pinch rolls, have their 80 shafts extended and are provided with sprockets 27 and 28 which are connected by a chain 29, so that all of said pinch rolls will be operated in unison. The upper feed-in pinch roll 5 is connected through gears 85 30 and 31, and a standard speed reducing unit 32 with a drive-motor 33.

In operation, the motors 21 and 33 will be energized so as to operate the pinch rollers 5 and 6 and 7 and 8 and the beater shafts 90 15. When the machine is in operation, a pack of sheets or plates consisting of either four or eight sheets will be fed into the bite of the feed-in pinch rollers 5 and 6, either manually or by automatic means, as desired.

The rollers 5 and 6 will feed the pack between the guides 9 and 10 and into the path of the beater arms 16 which will strike the pack alternately on the top and bottom 100

so as to alternately flex or bend the pack up and down against the edges of the solid sections 13 of the guides, thus breaking the bond or adhesions between the sheets and 5 causing the packs to open.

By alternately striking the pack on the top and bottom faces so as to bend the pack in opposite directions, the bends counteract each other so that the packs are delivered through the feed-out pinch rollers in 10 a relatively flat condition.

The relatively sharp bend caused by forcing the pack against the edges of the sections 13 of the guides 9 and 10 is also essential since it causes the adhesions between 15 the sheets to break more readily than would be the case if a large radius bend were made as would be the case if the sections 13 of the guides were spaced too widely or if the 20 guides were omitted.

While I have shown and described one specific embodiment of my invention it will be understood that I do not wish to be limited thereto, since various modifications may 25 be made without departing from the scope thereof, as defined in the appended claims.

I claim:

1. A pack opening machine for packs of sheets and plates comprising a main frame, 30 a pair of feed-in pinch rollers, a pair of feed-out pinch rollers, a pair of spaced guide members between said pairs of pinch rollers, a pair of beater members journaled intermediate said pairs of pinch rollers and 35 above and below said guide members so as to alternately strike the opposite faces of the packs to bend and flex said packs out of their normal line of feed, said guides being continuous between said beaters and 40 said feed-in pinch rollers and being spaced only sufficient to permit a workable clearance so that said beaters can force said packs to bend and flex along the edge of said continuous portion of said guides.

45. 2. A pack opening machine for packs of sheets and plates comprising a main frame, a pair of horizontal feed-in pinch rollers, a pair of horizontal feed-out pinch rollers spaced materially forward of said feed-in 50 pinch rollers, a pair of vertically spaced guide members between said pairs of pinch rollers, a pair of horizontally arranged vertically spaced rotary beaters journaled intermediate said pairs of pinch rollers and 55 above and below said guide members so as to alternately strike the top and bottom faces of the packs to bend and flex said packs out of their normal line of feed, said guides being continuous between said beaters and 60 said feed-in pinch rollers and being spaced only sufficient to permit a workable clearance so that said beaters can force said packs to bend and flex along the edge of said continuous portion of said guides.

65. 3. A pack opening machine for packs of

sheets and plates comprising a main frame, a pair of horizontal feed-in pinch rollers, a pair of horizontal feed-out pinch rollers spaced materially forward of said feed-in pinch rollers, a pair of vertically spaced 70 guide members between said pairs of pinch rollers, a pair of horizontally arranged vertically spaced rotary beaters journaled intermediate said pairs of pinch rollers and above and below said guide members so as to alternately strike the top and bottom faces of the packs to bend and flex said 75 packs out of their normal line of feed, said beaters being rotated at a materially greater speed than said pinch rollers so that said beaters will strike said packs at relatively close intervals along the pack and thereby work the entire area of the pack, said guides being continuous between said beaters and said feed-in pinch rollers and being spaced 80 only sufficient to permit a workable clearance so that said beaters can force said packs to bend and flex along the edge of said continuous portion of said guides.

In testimony whereof, I have hereunto set 90 my hand.

ARTHUR R. McARTHUR.
